ARITHMETIC TEACHING AID

Arden K. Ruddell, San Jose, and Gerald W. Brown,
Los Angeles, Calif.

Application February 28, 1955, Serial No. 34,729

Term of patent 14 years

(Cl. D25—1)

Fig. 1.

Fig. 3.

Fig. 2.

Fig. 1 is a front perspective view of an arithmetic teaching aid showing our new design.

Fig. 2 is a rear perspective view thereof, the central portion representing a surface of felt or flocking.

Fig. 3 is an end elevational view thereof.

The legible matter shown in broken lines in the drawing is for illustrative purposes only.

We claim:

The ornamental design for an arithmetic teaching aid, substantially as shown and described.
